UNITED STATES PATENT OFFICE.

GEORGE W. GOFF, OF EAST HAMPTON, CONNECTICUT, ASSIGNOR TO THE
EAST HAMPTON BELL COMPANY, OF SAME PLACE.

BELL.

SPECIFICATION forming part of Letters Patent No. 254,002, dated February 21, 1882.

Application filed December 24, 1881. (Model.)

To all whom it may concern:

Be it known that I, GEORGE W. GOFF, of East Hampton, in the county of Middlesex and State of Connecticut, have invented a new 5 Improvement in Team-Bells; and I do hereby declare the following, when taken in connection with the accompanying drawing and the letters of reference marked thereon, to be a full, clear, and exact description of the same, 10 and which said drawing constitutes part of this specification, and represents a sectional view.

This invention relates to an improvement in that class of bells which are constructed to be hung upon the harness of a horse, as for horse-ears, trucks, and other purposes, the object 15 being to simplify the construction of the bell, as well as to make it more durable than the usual construction of loop and strap; and the invention consists in a wire inserted through 20 a perforation in the head of the bell, with the tongue hung thereto upon the inside, that portion outside being bent into the form of an open-mouthed hook for conveniently hanging the bell upon the harness, as more fully hereinafter described.

A represents the bell, of common shape. Through its head end a perforation, *a*, is made. Through this perforation a wire is inserted, and should be very nearly the diameter of the 25 perforation, so that the bell will fit somewhat

closely upon the surface of the wire. Inside the bell an eye, B, is formed on the end of the wire, and into this wire the tongue C is hung. Outside the bell the wire is bent to form an open-mouthed hook, D. In making the bend 35 for the hook the wire is first bent backward near the head of the bell, so as to bring the hook substantially concentric with the bell, as shown. This back bend prevents any considerable play of the bell upon the wire or the wire 40 from slipping down through the bell.

This construction produces a bell very cheap and simple, not liable to get out of repair, carrying in itself the means for attaching the bell to the harness, and avoids the interlacing 45 and buckling of the strap, necessary where it is secured by means of a loop on the head end of the bell.

I claim—

The combination of the bell A, constructed 50 with a perforation through its head end and a wire inserted through said perforation, with the hammer hung to the inner end of the wire, the outer end bent to form an open hook, D, the bend serving also to secure the parts together, 55 substantially as described.

GEORGE W. GOFF.
